UNITED STATES PATENT OFFICE.

JESSE P. MILLER, OF TREES, LOUISIANA.

OIL-STORAGE SYSTEM AND METHOD OF PROTECTING STORED OILS.

1,186,417.

Specification of Letters Patent. Patented June 6, 1916.

Application filed September 10, 1913. Serial No. 789,166.

To all whom it may concern:

Be it known that I, JESSE P. MILLER, a citizen of the United States, residing at Trees, in the parish of Caddo and State of Louisiana, have invented new and useful Improvements in Oil-Storage Systems and Methods of Protecting Stored Oils, of which the following is a specification.

This invention is an improved oil storage system and an improved method of storing oil and protecting the same from explosion of gas and also from danger of ignition by lightning or otherwise, as hereinafter described and claimed.

15 The invention consists in an oil storage system including an oil storage tank closed against the admission of air and means to maintain a supply of gas above the oil in the tank and at a pressure exceeding that of the atmosphere to prevent an explosive mixture of gas and air from being formed in the tank.

20 The invention further consists in an oil storage system including an oil storage tank closed against the admission of air, means to maintain a supply of gas above the oil in the tank and at a pressure exceeding that of the atmosphere and means to regulate the pressure of the gas.

25 The invention further consists in the method of protecting oil in storage by excluding air from the oil container, maintaining a body of gas above the oil at more than atmospheric pressure and relieving gas pressure when the same becomes excessive.

30 The invention also consists in the arrangement and construction of devices herein-after described and claimed.

In the accompanying drawings:—Figure 40 1 is a plan of an oil storage system arranged in accordance with my invention. Fig. 2 is a transverse sectional view of the same on the plane indicated by the line $a-a$ of Fig. 1. Fig. 3 is a similar view on the plane indicated by the line $b-b$ of Fig. 1. Fig. 4 is a vertical sectional view, showing a modified arrangement of my improved oil storage system, Fig. 5 is a similar view, showing another modification.

45 50 In accordance with my invention, the oil storage system or "tank farm" comprises a series of oil storage tanks 1 of which there may be any suitable number. The storage tanks may be otherwise of any suitable construction, but must be closed against the admission of air. Gas supply means is also

employed and is here indicated as a pipe 2 which forms the part of a gas system of any kind in which gas is maintained at a pressure exceeding that of the atmosphere. 60 A gas feed pipe 3 which may be of the construction and arrangement here shown or of any other suitable construction and arrangement is connected at its intake end to the gas supply pipe 2 as at 4 and at this point a suitable gas regulator 5 is installed. At the discharge end of the gas feed pipe is a suitable check valve or other means to open under pressure from within the pipe and to close against the pressure without the pipe, 65 this valve being here indicated as a pop valve 6. The discharge end of the pipe is provided with a suitable fire protector 7, to prevent the ignition of gases escaping from the pipe by lightning or otherwise and this 70 fire protector is connected to earth by means of a suitable lightning conductor 8^a. The fire protector may be of any suitable type and construction and is not herein specifically claimed. Each of the oil storage tanks 1 is 75 connected to the gas feed pipe by a branch pipe 9, the said branch pipes being intermediate the ends of the gas feed pipe and each of the oil storage tanks being connected to the gas feed pipe independently of the 80 others.

85 My improved method of storing and protecting oil and the operation of my improved oil storage system is as follows:—Petroleum or other liquid hydrocarbon 90 which gives off inflammable gases is placed for storage in the closed tanks 1. These tanks as hereinbefore stated are closed against the admission of air and the gas emanating from the oil accumulates in the 95 tanks above the oil. To prevent the possibility of the entrance of air into the tanks and the forming of a highly inflammable mixture of gas and air in the tanks, the latter are also supplied with gas from the gas supply system or apparatus 2 through the gas feed pipe 3 and its branches 9, the gas regulator 5 being set so as to maintain gas pressure in the tanks somewhat in excess of atmospheric pressure. The only 100 means for the escape of gas from any of the tanks is through the valve 6 which is arranged at a distance from the tanks and forms a common gas escape means therefor and this valve 6 is weighted or otherwise arranged or constructed to keep the 105 said valve closed under ordinary condi-

tions and to permit it to be opened by pre-determined gas pressure in the tanks and gas feed pipe, which gas pressure, sufficient to open the valve 6 is far below that 5 which would become dangerous or cause an explosion of gas in the tanks. Hence, the explosion of gas in the tanks is prevented, and owing to the fact that the tanks are also kept supplied with gas below such 10 pressure as to be dangerous and yet above atmospheric pressure, air is effectually prevented from entering the tanks and forming highly inflammable explosive mixture of gas and air therein and danger from this 15 source is also avoided.

When the gas in the tanks exceeds a pre-determined pressure, slightly above atmospheric pressure, the gas regulator 5 automatically closes and the valve 6 opens, thus 20 permitting the pressure of gas in the tanks to be relieved but the valve 6 closes against the back pressure and, hence, prevents air from entering any of the tanks.

The fire protector 7 arranged at the gas 25 vent of my improved oil storage system prevents the ignition of the vented gases by lightning or otherwise and owing to the fact that the tanks are closed to the admission of air and have no other gas vent than 30 that provided by the valve 6 which is at a distance from the tanks, all danger of fire or of explosions at the tanks is avoided. The lightning conductor 8 which leads from 35 the fire protector to the earth is an additional element of safety with which my oil storage system is provided.

In Fig. 4, I show a modified form of my improved oil storage system in which the tanks 1^a are arranged in series, each pair of tanks being arranged together and connected by a pipe 8, the first tanks of the series being connected to the gas regulator by a pipe 9^a and the last tank of the series being connected by a pipe 10 to the gas escape. 40

In Fig. 5, I illustrate another modified form of my improved oil storage system in which the last tank 1^b of the series is provided with a gas escape valve 11 directly in its top, as it is not essential, in accordance 45 with my invention, that the vent of the gas should discharge at a distance from the tank. 50

I claim:—

1. An oil storage system comprising a 55 plurality of closed oil containers, a gas pipe to all the containers and in communication therewith and a constant pressure regulator in the pipe and common to all the containers. 60

2. An oil storage system comprising a plurality of closed oil containers, a gas pipe common to all the containers and communicating therewith and a constant pressure regulator in the gas pipe in advance of the containers. 65

In testimony whereof I affix my signature in presence of two witnesses.

JESSE P. MILLER.
